1

This invention relates to circuits comprising electric discharge tubes which are suitable for short operation at short and ultra-short wavelengths, i. e. wavelengths of several metres down to approximately one centimetre and which comprise at least a cathode, a control grid and an output electrode. The last-named electrode in a normal triode, tetrode or pentode is the anode; for the centimetric range it is substantially only triodes that enter into account.

In order to make such tubes serviceable, for example as amplifiers, at as short a wavelength as possible, efforts have been directed towards minimizing the capacity between the input electrode and the common electrode on the one hand and between the common electrode and output electrode on the other hand. At wavelengths that are not excessively short the cathode is usually the common electrode. With tubes comprising disc-shaped electrode leads suitable for ultra-short waves, the control grid is usually the common electrode. The capacity between the different electrodes depends not only upon the surface area of the electrodes and their relative spacing but also upon unavoidable parasitic capacity.

If that part of the capacity between the electrodes which is directly proportional to the active surface is termed the effective capacity, it is well known that the effective capacity of a simple flat arrangement equals

$$\frac{0}{4\pi d}$$

wherein 0 =the active electrode surface and d =the spacing. For more intricate arrangements the effective capacity may be computed as the sum of a number of terms or in an integral form. That fraction of the total capacity that is not constituted by the effective capacity as defined will hereinafter be termed the "ballast capacity."

In view of the necessity for maximum reduction of the tube capacities it is first essential to minimize the ballast capacity. However, for each electrode arrangement there is a minimum which may not be passed owing to the capacity of the wiring and supply conductors. For tube constructions comprising flat electrodes and lead-through discs sealed into the wall of the tube, this minimum is lower than for tubes with a concentric arrangement and pin-shaped electrode leads.

As a rule the effective capacity must be comparatively high, since in particular the cathode

2

surface must usually not be loaded above a given current density and the surface area must satisfy the desired power requirement.

According to the present invention in a circuit comprising an electric discharge tube for short and ultra-short waves, the tubes including at least a cathode, a control grid and an output electrode, the product of the ratios of the effective capacity and the ballast capacity between 10 the input electrode and common-electrode and between the common electrode and the output electrode lies between $\frac{1}{4}$ and 4, each of these ratios has a value between $\frac{1}{2}$ and 2. The product of the two ratios preferably equals or approximately equals unity. In the optimum each of the two ratios equals unity.

The power gain attainable with the tube in the case of complete matching is a maximum if the two ratios and the product thereof are equal to each other and unity respectively. If the two ratios are each 2 or $\frac{1}{2}$ the attainable power gain is 25% lower than the maximum, again with complete matching. This holds if the ohmic dampings preponderate relatively to the electronic dampings as is usually the case at very high frequencies. If the electronic damping is comparatively high, the power decrease is reduced. The feedback due to the self-inductance of the grid wires of the tube should be small and in absolute value substantially equal the feedback due to the capacity between the anode and cathode.

The reasoning behind the choice of the aforesaid ratios and this product may be explained as follows. The maximum attainable power gain 35 depends upon the mutual conductance of the tube, which generally has a complex value for high frequencies. Furthermore the power gain depends upon the input damping, the output damping and the feed-back in the tube. As a rule, the power gain with a non-excessive feed-back will approximately be inversely proportional to the product of the input- and output-damping, expressed as conductances, and substantially directly proportional to the square of the absolute value of the mutual conductance. At very high frequencies the input- and output-dampings largely depend upon the respective total capacity, effective and ballast capacity together, since the charging and discharging of these capacitances must take place through the series-resistors formed by the supply conductors and does not appreciably depend upon the size of the electrode surfaces.

The correctness of the aforesaid criteria may

be conformed from the considerations in an article by Knol and Van der Ziel in Philips Research, vol. 4, pages 168 to 178, 1949. Referring to Formula 22 therein for the maximum power gain $g_{\max}$ of an arbitrary four terminal network in the case of optimum tuning and matching at the input and output side and an arbitrary given feedback, it holds that

$$g_{\max} = \frac{R_1 R_4}{R} \left(\frac{1 + \beta_2^2}{2} \right) [2 - \delta(1 - \beta_1 \beta_2) + 2\sqrt{1 - \delta(1 - \beta_1 \beta_2 - \frac{1}{4}\delta^2(\beta_1 + \beta_2)^2)} - 1]$$

R_1 = input resistance = effective part of $\frac{V_{\text{input}}}{I_{\text{input}}}$ with open output

R_2 = feedback resistance = effective part of $\frac{V_{\text{output}}}{I_{\text{input}}}$ with short-circuited input

R_3 = forward resistance = effective part of $\frac{V_{\text{input}}}{I_{\text{output}}}$ with short-circuited output

R_4 = output resistance = effective part of $\frac{V_{\text{output}}}{I_{\text{output}}}$ with open input

β_1 = tan phase angle, feedback admittance

β_2 = tan phase angle, forward admittance

$$\delta = \frac{R_1 R_4}{R_2 R_3}$$

All the admittances consist of an electronic and a nonelectronic part, the latter consisting of the ohmic losses. The electronic part is invariably proportional to the active surface and to the effective capacity. The non-electronic parts are proportional to the square of the total capacity.

If in the aforesaid formula everything is expressed in the ratio between the effective capacity and ballast capacity it is found that $g_{\max}$ as a function of this ratio has a maximum if it equals unity.

In order that the invention may be more clearly understood and readily carried into effect, reference will now be made to the accompanying drawings, given by way of example, in which:

Fig. 1 is a cross-section of the electrode system of a known double pentode and

Figs. 2 and 3 are longitudinal sections of the electrode systems of a known triode comprising disc-shaped lead-out members and of a triode comprising disc-shaped lead-out members for use according to the invention.

The dimensions of the double pentode shown in Fig. 1 appear from the scale given. For each pentode, 1 denotes the cathode, 2 the control grid, and 3 the screen grid. The suppressor grid 4 is constructed as an apertured screen and is common to both pentodes. In each system, the anode 5 consists of two plates. The electrode system is surrounded by a screen 6 and the envelope of the tube is shown at 7. In a tube of this construction which is marketed under the type number EFP 50 the active cathode length is 18 mms. The grid capacity $C_g = 9.4$ pf., the anode capacity $C_a = 5.5$ pf. for each pentode. With this known tube the power gain at a wavelength of 1 metre is only 2.5. When using the same constructional details, for example the cross-section of the electrode system and the wiring within the tube, but reducing the length of the system we found that

for an effective system length of 6 mms. the maximum attainable power gain amounted to 10. Due to this reduction the total power available decreases materially but this is not objectionable in many applications, for example low-level amplifiers. With the reduced length $C_g = 5.3$ pf. and $C_a = 2.5$ pf. The term "pf." wherever used herein denotes piccofarad or micro-microfarad.

In this electrode system, it may be taken that the ballast capacity is present only at the ends of the electrode system and in the wiring, from which it can be deduced that for the reduced grid capacity = 2.05 pf. and the ballast capacity = 3.25 pf. For the reduced anode the effective capacity is 1.5 pf. and the ballast capacity = 1.0 pf., the two ratios between effective capacity and ballast capacity then being

$$\frac{2.05}{3.25} = 0.63$$

and

$$\frac{1.5}{1} = 1.5$$

and the product 0.95.

For the known tube the ballast capacities are the same and the effective capacities for grid and anode are 6.15 and 4.5 pf. respectively, so that the ratios are

$$\frac{6.15}{3.25} \approx 1.9$$

and

$$\frac{4.5}{1.0} = 4.5$$

and the product = 8.5.

In the known tube shown in Fig. 2, a cylindrical anode block 8 is sealed to a grid disc 10 by means of a conical glass head 9. A glass ring 11 constitutes the joint between the grid disc and a cathode cylinder 12. By means of glass beads two heater-supply conductors 14 and a cathode-supply conductor 16 are sealed in the base 13. The exhaust tube is designated 15, the filament 17 and the cathode 18. The active surface of the cathode carries a thin oxide layer (not shown). The cathode 18 is welded with the aid of foil 19 to the flanged cylinder 21. Its flange is enclosed between two ceramic rings 22 and 23 and centred by a ring 24 contacting with the supply conductor 16. The cathode is electrically separated from the cylinder 12 by means of an insulating ring 25. The construction is clamped together by means of four springs 26 extending from ring 27 and strained by cylinder 28. The ceramic ring 22 bears against copper foil 29 resting on the cathode side of grid ring 30 which has secured thereto a plurality of grid wires. By means of enamel 32 three arms 31 are secured in three slots provided at angles of 120° in ring 22. As stated this construction is known; it is given to permit direct contrast with a corresponding tube, for use according to the invention shown in Fig. 3. In Fig. 3 the cathode grid and anode discs are designated 31, 32, 33 respectively, 34 being a cylindrical anode. The grid ring 35 rests with its wire-wound side 36 against the grid disc. A porous

tungsten hood containing a supply of barium-strontium oxide 38 is designated 37. The cathode is connected to the cathode disc through foil 39. This tube is shown in lesser detail than the tube shown in Fig. 2, since there is no necessity to describe points following known tube-technique.

In the following table constructional data and properties are given for the known tube shown in Fig. 2 and for the tube shown in Fig. 3.

	Fig. 2	Fig. 3
Diameter of anode and cathode.	4.5 mms.	3 mms.
Surface area of cathode.	16 sg. mms.	7 sg. mms.
Type of cathode.	Oxide cathode.	Metal cathode.
Distance to centre of grid wires from—		
Cathode.	17.5 μ	40 μ .
Anode.	250 μ .	250 μ .
Thickness of grid wires.	7.5 μ .	10 μ .
Pitch of grid wires.	25 μ .	50 μ .
Cathode-grid spacing.	With distance foil.	Through bulb wall.
Capacity, cathode-grid total.	9.4 pfs.	2.2 pfs.
Effective.	8.4 pfs.	1.5 pfs.
Ballast.	1.0 pf.	0.7 pf.
Capacity, grid-anode total.	0.87 pf.	0.57 pf.
Effective.	0.62 pf.	0.24 pf.
Ballast.	0.25 pf.	0.33 pf.
Ratio between effective and ballast capacity:		
Cathode-grid.	8.4.	2.1.
Grid-anode.	2.5.	0.7.
Product of ratios between effective and ballast capacity.	21.	1.5.
Attainable power gain at wave length.	10 $\times$ 7.5 cms.	10 $\times$ 7.5 cms.
Supplied power.	0.5 w.	0.5 w.
Corresponding anode current and mutual conductance.	25 ma.	30 ma.
	50 ma./v.	13 ma./v.

The capacities stated in the table are those of the tube without the capacities through the glass of the bulb. It is obvious that in the tube shown in Fig. 3 the total capacity between cathode and grid is materially lower. Moreover, the cathode-grid spacing through the bulb wall is simpler than through the foil shown in Fig. 2. The mutual conductance of the tube shown in Fig. 3 is one fourth of that shown in Fig. 2 and notwithstanding that, the power gain at the same wavelength similarly corresponds to the power supplied. This equally-satisfactory operation, despite the larger cathode-grid spacing and the low mutual conductance, is for the major part due to the favourable ratio between effective capacity and ballast capacity.

What we claim is:

1. An electric discharge tube comprising a cathode, an output electrode, and a common electrode interposed between said cathode and output electrode, said common electrode and said cathode electrode having active surface portions spaced apart a distance at which there is a given effective capacitance and a given ballast capacitance between said cathode and said common electrode, the ratio of said capacitances being between $\frac{1}{2}$ and 2, said output electrode and said common electrode having active surface portions spaced apart a distance at which there is a given effective capacitance and a given ballast capacitance between said output and common electrode, the ratio of the latter capacitances being between $\frac{1}{2}$ and 2, said electrodes further being spaced from each other a distance at which the product of said ratios is between $\frac{1}{4}$ and 4.

2. An electric discharge tube comprising a cathode, an output electrode, and a common electrode interposed between said cathode and output

electrode, said common electrode and said cathode electrode having active surface portions spaced apart a distance at which there is a given effective capacitance and a given ballast capacitance between said cathode and said common electrode, the ratio of said capacitances being between $\frac{1}{2}$ and 2, said output electrode and said common electrode having active surface portions spaced apart a distance at which there is a given effective capacitance and a given ballast capacitance between said output and common electrode, the ratio of the latter capacitances being between $\frac{1}{2}$ and 2, said electrodes further being spaced from each other a distance at which the product of said ratios is unity.

3. An electric discharge tube comprising a cathode, an output electrode, and a common electrode interposed between said cathode and output electrode, said common electrode and said cathode electrode having active surface portions spaced apart a distance at which there is a given effective capacitance and a given ballast capacitance between said cathode and said common electrode, the ratio of said capacitances being approximately unity, said output electrode and said common electrode having active surface portions spaced apart a distance at which there is a given effective capacitance and a given ballast capacitance between said cathode and said common electrode, the ratio of said capacitances being approximately unity, said output electrode and said common electrode having active surface portions spaced apart a distance at which there is a given effective capacitance and a given ballast capacitance between said output and common electrode, the ratio of the latter capacitances being approximately unity, said electrodes further being spaced from each other a distance at which the product of said ratios is approximately unity.

4. An electric discharge tube comprising a cathode, an output electrode, a common electrode interposed between said cathode and output electrode, said common electrode and said cathode electrode having active surface portions spaced apart a distance at which there is a given effective capacitance and a given ballast capacitance between said cathode and said common electrode, the ratio of said capacitances being between $\frac{1}{2}$ and 2, said output electrode and said common electrode having active surface portions spaced apart a distance at which there is a given effective capacitance and a given ballast capacitance between said output and common electrode, the ratio of the latter capacitance being between $\frac{1}{2}$ and 2, said electrodes further being spaced from each other a distance at which the product of said ratios is between $\frac{1}{4}$ and 4, and terminal wires for said common electrode, said terminal wires having a self-inductance at which feed-back introduced through inter-electrode capacitance between the cathode and output electrode.

5. An electric discharge tube comprising a cathode comprising a hollow body of refractory metal having a cavity therein, one wall of said body adjoining said cavity being porous, and a supply of alkaline earth oxides in said cavity, an output electrode, and a common electrode interposed between said cathode and output electrode, said common electrode and said cathode electrode having active surface portions spaced apart a distance at which there is a given effective capacitance and a given ballast capacitance between said cathode and said common electrode, the ratio of said capacitances being between $\frac{1}{2}$ and 2, said output electrode and said common electrode having active surface portions spaced apart a distance at which there is a given effective capacitance and a given ballast capacitance between said output and common electrode, the ratio of the latter capacitance being between $\frac{1}{2}$ and 2, said electrodes further being spaced from each other a distance at which the product of said ratios is unity, said terminal wires having a self-inductance at which feed-back introduced through inter-electrode capacitance between the cathode and output electrode.

and 2, said electrodes further being spaced from each other a distance at which the product of said ratios is between $\frac{1}{4}$ and 4.
